FIG. 1

FIG. 2

FIG. 3

FIG. 4

FIG. 5

FIG. 1 is a perspective view of a golf putting target trophy showing our new design;

FIG. 2 is a right end elevational view;

FIG. 3 is a left end elevational view;

FIG. 4 is a back elevational view; and

FIG. 5 is a front elevational view.

The dominant features of our design reside in the full line showing of the drawing.

The broken line golfing figure in FIG. 1 has been omitted from the remaining figures for convenience in illustration.

We claim:

The ornamental design for a golf putting target trophy, substantially as shown and described.
